UNITED STATES PATENT OFFICE.

BERNHARD H. RUETER, OF BURLINGTON, WISCONSIN.

STUFFING FOR HORSE-COLLARS.

SPECIFICATION forming part of Letters Patent No. 694,198, dated February 25, 1902.

Application filed March 14, 1898. Serial No. 673,855. (No model.)

To all whom it may concern:

Be it known that I, BERNHARD H. RUETER, a citizen of the United States, residing at Burlington, in the county of Racine and State of Wisconsin, and whose post-office address is Burlington, Wisconsin, have invented certain new and useful Improvements in Stuffing for Horse-Collars; and I do declare the following to be a full, clear, and exact description of the invention, such as will enable others skilled in the art to which it appertains to make and use the same, reference being had to the accompanying drawing, and to the figures of reference marked thereon, which form a part of this specification.

My invention relates to horse-collars; and it has for its object to provide an improved stuffing for the collar with the view of absorbing the moisture from the face of the collar, thus preserving the form and shape and preventing the leather at the face becoming hard from absorption of moisture. One objection to employing long wool by itself as a stuffing next to the face of horse-collars is that the wool, while absorbing moisture to a more satisfactory extent than other materials, will, however, become matted from the absorption, and then the shape or form of the face of the collar is seriously impaired and the power of the wool to absorb diminished correspondingly to the extent to which it may become matted. The objection to the use of sponge alone is that it will not retain its place or position when formed in small pieces, as it lacks the quality of adhesion, and consequently the shape or form of the face of the collar is impaired. With the view of overcoming these objections and forming a stuffing material that will possess the desirable qualities for preservation of the shape or form and the softness of the face of the collar I form a stuffing material out of wool and particles of sponge intermingled, so that the adhesive qualities of the wool will be availed of to hold the particles of sponge in position and the properties of the sponge will be availed of to prevent the wool becoming matted, the absorbent properties of the two materials being availed of to absorb the moisture from the leather along the face of the collar and transmit the same to the straw stuffing back of the stuffing material of wool and sponge,

so that the straw will be given the opportunity to take up the moisture thus transmitted and at the same time perform its function of presenting a firm backing to the rear face of the collar, the shape of the inner face of the collar being thus preserved and the leather along the face being prevented from hardening.

To the accomplishment of the foregoing and such other advantages as may be derived the invention consists in the stuffing material of wool and particles of sponge and applied next to the face of the collar, as hereinafter specified, reference being had to the accompanying drawing, illustrating the invention, and in which is represented a perspective of a part of a horse-collar with the invention applied thereto.

In the drawing the numeral 1 designates a collar of any approved form and well-known general features of construction. This collar is provided with ordinary stuffing material for the fore-wale 2 and with a stuffing of straw or other suitable material in the after-wale at the side adjacent to the fore-wale, the other portion of the after-wale next to the face 3 of the collar being stuffed with a material composed of wool 4, preferably of a long staple, and particles of sponge 3, which is preferably cut, chopped, or picked into small pieces. The wool and the particles of sponge are intermingled, so that the adhesive qualities of the wool hold the particles of sponge in place and the particles of sponge will prevent the wool from matting. The stuffing material thus formed and applied absorbs the moisture which the leather face receives from the horse and transmits this moisture to the straw stuffing at the rear, which in turn absorbs the moisture, thus taking it away from the face of the collar, and in that way preventing the leather at the face from hardening. By reason of the properties mentioned in the wool and the sponge the advantages of both of these materials are obtained and the disadvantages of either alone overcome by the presence of the other, and thus it enables the form or shape of the face of the collar to be preserved, which would be destroyed to a greater or less extent if either the wool or the sponge were used without the presence of the other for the reasons before set forth. A firm back-

ing is formed for the sponge and wool by the straw stuffing at the rear, and the necessary firmness is thus imparted to the after-wale at the side adjacent to the fore-wale and an 5 economical stuffing provided.

It is obvious that where the stuffing to the collar as such is carried to a pad over the neck the pad becomes practically a part of the collar, and the stuffing is of the same relative 10 value as when applied to the body or wales of the collar.

Having described my invention and set forth its merits, what I claim is—

1. The improved stuffing for horse-collars 15 consisting of a composition of matter composed of particles of sponge and fibers of wool intermingled so as to bring the fibers of wool between the particles of sponge to hold the

sponge particles in position and prevent matting of the wool fibers, substantially as de- 20 scribed.

2. In a horse-collar the stuffing for preserving the shape of the collar consisting of particles of sponge and fibers of wool intermingled so as to bring the fibers of wool between 25 the particles of sponge, and an absorbent backing of straw placed back of the intermingled wool fibers and sponge particles, substantially as described.

In testimony whereof I affix my signature 30 in presence of two witnesses.

BERNHARD H. RUETER.
